Primary Examiner — Wendy L Arminio*Assistant Examiner* — Maheen Khurshid(57) **CLAIM**

The ornamental design for a strap, as shown and described.

DESCRIPTION

FIG. 1 is a front view of a strap showing my new design;
 FIG. 2 is a rear view thereof;
 FIG. 3 is a top view thereof;
 FIG. 4 is a bottom view thereof;
 FIG. 5 is a left side view thereof;
 FIG. 6 is a right side view thereof;
 FIG. 7 is a perspective view thereof; and,
 FIG. 8 is another perspective view thereof.

The dash-dash broken lines depict portions of the strap that form no part of the claimed design. The dash-dot-dash broken lines illustrate a boundary of the design that form no part of the claimed design.

1 Claim, 8 Drawing Sheets(56)
